SLIDING DOOR

Wilhelm Abendroth, Dusseldorf, Germany

Application May 14, 1938, Serial No. 207,959
In Switzerland October 29, 1937

1 Claim. (Cl. 16—88)

This invention relates to a sliding door which is suspended either directly or by means of an adjusting device from the lower arm of an approximately U-shaped supporting rail which is supported by means of two or more balls which run in the lower arm of a fixed running rail which is also approximately U-shaped.

One novel feature of the sliding door of the present invention is that the upper arm of the rail from which the door is suspended is guided, when the door is moved, in a straight line in the upper arm of the fixed rail by a bulge or projection which is pressed upwardly out of the supporting rail and is situated in a vertical plane passing through the centres of the balls; the distance between the top of the projection and the bottom of the balls is approximately equal to the distance between the two arms of the running rail, so that, when the door is moved, the balls run on the lower arm and the projection slides on the upper arm of the running rail. The supporting rail is therefore well and securely guided in the running rail and cannot be lifted up out of contact with the balls.

Another novel feature of the invention is that the upper arm of the supporting rail is provided with two oppositely situated running edges which make contact with the balls approximately half way down the upper half of the balls while the balls themselves rest wholly above the track on the running rail so that, when the door is moved, the balls roll with their full periphery on the track of the running rail, whereas the supporting rail moves on a circle of smaller diameter. The effect of this is that the distance through which the supporting rail moves relatively to the balls is small in comparison with the total displacement of the door, and also the distance travelled by the balls themselves is less than the total displacement of the door.

A further novel feature of the invention consists in the arrangement of the balls and in the means for keeping them apart from one another. For this purpose each ball is fitted in a cage consisting of two rings, and the cages are connected together by means of a rod which is disposed above the balls in the bulge or projection on the supporting rail. By this means the balls are kept at a fixed distance apart when the door is moved and are prevented from falling out when the supporting rail is placed in the running rail during assembly.

A sliding door constructed in accordance with the invention is illustrated by way of example in the accompanying drawing, in which

Figure 1 is a part longitudinal section through the door.

Figure 2 is a cross section on the line A—B of Figure 1.

Figure 3 is a longitudinal elevation of the two ball cages after removal from the door together with the rod by which they are connected, and

Figure 4 is a section on the line C—D of Figure 3.

Referring to the drawing, *a* represents the door, which is suspended from the lower arm *c* of a supporting rail *d*. The height of the door can be adjusted by means of two adjusting devices *b* consisting of screws and nuts. The reference *e* represents a running rail which is fixed in position and has a lower arm *s* which forms the track *f* and an upper arm *r* of which the part *g* acts as a guide. The references *h* represent two balls on which two running edges *i* provided on the supporting rail *d* can run. The upper arm *l* of the supporting rail *d* is provided with an upward bulge or projection *m* which is situated in a vertical plane through the centre of the balls *h*. This projection is guided by the part *g* of the upper arm *r* of the running rail *e*. The lowest points of the two balls *h* are supported on the track *f* of the lower arm *s* of the running rail *e* and each of them is carried in a cage which consists of two rings *n* connected by a bar *o*. The two cages are connected together by a rod *p* which is welded on above the bars *o*. The connecting rod *p* is arranged inside the bulge *m* and above the pins *q* connecting the two vertical side walls *k* of the upper arm *l* of the supporting rail *d*. The pins *q* are riveted on after the two cages together with the connecting rod *p* have been placed in position. The two running edges *i* of the upper arm *l* of the supporting rail *d* make contact with the two balls *h* approximately halfway down the upper half of the balls and the distance between the track *f* and the part *g* of the running rail *e* is such that there is only quite a small amount of play between the arms of the running rail *e* and the upper arm *l* of the supporting rail *d* and the two balls *h* which they engage, the balls resting on the track *f* of the running rail *e*.

By this means the door can be moved easily and the movement of the balls relatively to the supporting rail is only small. Any tendency of the balls to over-run the supporting rail or to lag behind is obviated and the balls and the supporting rail can easily be assembled in the running rail. The running rail is screwed on after the suspension device has been completely

assembled, the supporting rail being moved sideways so that the places where the screws are to be fixed are accessible.

I claim:

- 5 A door hanger for sliding doors comprising a track member of substantially U-shape in cross section with the side arms thereof disposed in vertically spaced horizontal planes defining upper and lower track guides, a door supporting member of substantially U-shape in cross section having the side arms thereof horizontally disposed with the upper arm disposed between the upper and lower arms of the track member 10 in opposed relation, balls and a cage therefor 15 carried by the door supporting member between the upper arm of the door supporting member

and the lower track guide of the track member and riding on the lower track member and the upper arm of the door supporting member being longitudinally upset intermediate the side edges thereof to form a longitudinally extending rib for riding contact with the upper track guide of the track member, and said upper and lower track guides being mutually transversely curved with the door supporting member capable of limited swinging movement transversely of the track member with the ball and rib maintaining constant engagement with said track guides to prevent vibratory movements of the door supporting member relative to the track member. 10 15
